(74) Attorney, Agent, or Firm—McDermott Will & Emery LLP

(57) **CLAIM**

The ornamental design for a razor handle, substantially as shown and described.

DESCRIPTION

FIG. 1 is a perspective view of the razor handle showing the new design;

FIG. 2 is a front view of the razor handle;

FIG. 3 is a rear view of the razor handle;

FIG. 4 is a side view of the razor handle;

FIG. 5 is another side view of the razor handle;

FIG. 6 is a top view of the razor handle; and,

FIG. 7 is a bottom view of the razor handle.

The broken lines are shown for illustrative purposes only and form no part of the claimed design.
